UNITED STATES PATENT OFFICE.

FREDERICK L. MCGAHAN, OF LOS ANGELES, CALIFORNIA; VIOLA K. WALKER, ADMINISTRATRIX OF SAID FREDERICK L. MCGAHAN, DECEASED, ASSIGNOR TO THE PURPOSED MIND DEVELOPMENT SECURITY ASSOCIATION OF THE WORLD, A TRUST COMPANY.

FAN.

1,423,348.

Specification of Letters Patent. Patented July 18, 1922.

Original application filed October 14, 1918, Serial No. 258,127. Divided and this application filed December 8, 1919. Serial No. 343,354.

To all whom it may concern:

Be it known that I, FREDERICK L. MCGAHAN, a citizen of the United States, residing at the city of Los Angeles, in the county 5 of Los Angeles and State of California, have invented certain new and useful Improvements in Fans, of which the following is a specification.

This is a division of an application filed 10 by me October 14, 1918, serially numbered 258,127, which has matured into Patent 1,324,427.

This invention relates to suction means in combination with a steam turbine of the 15 radial impulse type, and is illustrated as applied to the auxiliary driving of a locomotive engine, with a construction suitable for the purpose of drawing smoke, gases, sparks and other products of combustion 20 from the fire-box and smoke-box of an engine, and then forcing the same through the turbine to mingle with the steam therein.

The object of the invention is to draw 25 the smoke and products of combustion from the smoke-box and after super-heating or re-heating steam which has been once utilized, returning these gases and products of combustion back to the fire-box to be re-burned. Moreover, this mechanism eliminates 30 wasteful and objectionable gas, smoke, sparks, and cinders by drawing the same out of the firebox and returning the solid particles thereto for further combustion. Other economies, advantages, and im- 35 provements will hereinafter appear.

In the accompanying drawings forming part of this specification and in which like numbers of reference denote like parts wherever they occur,

40 Fig. 1 is a vertical section through a turbine equipped with the fan or suction means of this invention.

Figure 2 is a plan view of the fan.

45 Figure 3 is a fragmental sectional perspective of the fan.

Passages 19 are conveniently connected to the turbine 6. Steam pressure is admitted into said pipe, and in applicant's prior Patent 1,324,427 the steam thus admitted is the exhaust from the usual expansion cylinders of steam engines. This steam passes through pipe 19 and thence into the 50 chamber 20 surrounding the revoluble rotor

21 having helical grooves in its surface adapted to receive frictional and impelling 55 contact from the incoming steam, thereby deriving its rotary motion and driving shaft 7.

Having thus energized the turbine 6, the steam passes through exhaust pipes 25 and 60 may be used to energize or actuate another turbine (not shown).

Each rotor 21 is of substantially the same construction and mounted and connected in substantially the same manner. Upon the 65 support 26 is fastened a ball-race 27, which bears the bottom of the rotor 28.

The fan 29 has a hub 90 fixed to the shaft 7 having a plurality of cups 91 adapted to connect to the flange 34. 70

The cups 91 open in the direction toward which they rotate, tending to force the intake. The shape within each cup diverts the air from its direction when admitted to a direction approximately at an angle of 75 90 degrees thereto.

Fan 29 draws hot air, smoke and cinders through pipes 30 from the top of the firebox, into the hollow chamber 50 of the rotor 21, and thereby the steam that enters chamber 20 through pipes 19 is reheated or super-heated, because the hot flames and gases heat the metal of the rotor 21 thereby reheating and drying the exhaust steam from the cylinders, after the said steam enters the chamber 20. 80 A ball race 27 co-operates with a groove in the bottom 28 of rotor 21 and a groove in supports 26 and 31, also, a ball race 32, co-operates, with a groove 33 in the flange 34 of the fan 29, and a groove 35 in the rotor housing 36, thereby allowing the rotor 21 to rotate freely as impelled by the action of the steam admitted through pipes 19, upon the helical grooves 37, and, 85 thereby rotating shaft 7, to which is fixed the said rotor 21. After the steam has passed through the chamber 20 of the helical grooves 37, it then passes into the chamber 38 of the support 26 and thence through pipe 25.

The steam passes through the exhaust pipes 25, preferably to another turbine or motor (not shown); however, it is not necessary so far as the present case is concerned, that the exhaust steam is so utilized. 105

The smoke, soot, cinders, and the like are

drawn into the turbine 6 through the pipe 30, from the fire-box, by the suction caused by the fan 29, and are drawn through the said fan into the chamber 50 of the rotor 21. 5 After the smoke has been drawn into the chamber 50 by action of fan 29 (which also draws the cinders and sparks from the fire-box, flue, or smoke-pipe 30) steam is admitted into the said chamber 50 through as 10 many valve orifices 51 as will properly condense said smoke, sparks, cinders, and soot by its being rapidly revolved and churned therein, so that, after its exit from turbine 6, same may be discharged through a stoker 15 back into the fire-box.

Piston compression blades 72 are helical in form and may be of any desired pitch. Said blades 72 are held against the highly ground surface of the rotor housing 36 at 20 73 by means of flat zigzag springs 74, said springs 74 being tempered to hold blades 72 in a fixed position against the said surface 73.

The opening of valves 52 is accomplished 25 through a flyball governor, having balls 53 on the end of a bell-crank lever 54, pivotally bolted to the flange 55 and the opening of valves 52 is brought about by the sleeve 60, cam wheel 62 having the hub 61, all operating as fully described in my prior Patent 30 No. 1,324,427.

The path of the steam is indicated by arrows in Fig. 1 and, as shown, the steam passes through an open valve, while the 35 other two valves are closed; illustrating that one valve may be opened while the other remains closed.

The steam, in its predetermined path, and the smoke pass through the openings 75 between the ribs 76. Ribs 76 are adapted to the hub 77, and the bottom of the rotor 28, and the smoke and gases pass into the chamber 78 of the support 26, and thence into the pipe 79, after which the mixture of smoke, 45 steam, sparks, and soot is carried by steam pressure and fan action, to be reburned in the fire-box.

On the rotor housing 36, is secured by bolts 81, the cap plate 80, having a center 50 hub 82, in which the shaft 7 rotates; and, at the bottom or smaller diameter of the rotor housing 26, is a flange 83, which is secured to the support 26 by means of bolts 84.

On the end of the shaft 7, there is fixed a 55 worm 85 and a worm wheel 86, but it is evident that bevel gears, spiral gears, spur gears, and the like, could be used as well as those shown, with a shaft 87 fixed to the driven member 86, which shaft may be the 60 axle of the locomotive wheels.

One object of the turbine 6 and the vacuum fan 29 is to create a draft from and through the fire-box, taking by suction any back pressure from the cylinders 5 and the piston blades 72 of turbine 6, giving the same 65 condition that is caused by the jet condenser in the well-known stationary engine. A further object is to draw all smoke, cinders, and sparks through the vacuum fan 29 and to keep a more even draft, just the necessary 70 draft to create and regulate a perfect blaze, in the fire-box and through the flues of the locomotive.

The separate driving increases the pulling power of the engine. A great advantage is 75 acquired, also, by the superheating of the steam in the interior of the turbine rotor 21 (chamber 50) of the locomotive turbine 6, due to the draft thereinto by the adjacent fans 29 of the hot air direct from the fire-box through pipes 30 this superheated steam being further utilized.

While the turbine is herein illustrated and described as utilized in connection with a locomotive engine, it can be used in other 85 situations, in which event water or steam may be used as the motive power.

Having thus described this invention, it is obvious that many minor changes in the form, arrangement and order of parts and their materials and mode of construction may be made without departing from the spirit of this invention or the scope of the following claims.

I claim:

1. A fan of the character described, comprising a plurality of blades radiating from the hub, said blades each forming a member having a concaved and a convexed surface terminating in straight edges radiating from the hub and in the arc of a circle, the concaved surface substantially facing in the direction of the axis of the fan, said blades being positioned relative to the hub to further provide an entrance into said concaved surface, which entrance faces in the direction of rotation of the fan.

2. A fan of the character described, comprising a plurality of members radiating from a hub, said members being formed with a concaved and a convexed surface terminating in straight edges radiating from the hub and in the arc of a circle, the concaved surface being positioned relative to the hub so as to gather air therein during its rotation 110 and to direct the same in a direction substantially parallel to the axis of the fan.

In testimony whereof I hereunto affix my signature.

FREDERICK L. McGAHAN.
